Inventor:

Frank D. Polhemus,
Spear Middlebush & Spear
Atty's.

UNITED STATES PATENT OFFICE.

FRANK D. POLHEMUS, OF ATLANTIC CITY, NEW JERSEY.

AUTOMATIC LUBRICATOR FOR SWITCH-POINTS.

1,239,719.

Specification of Letters Patent. Patented Sept. 11, 1917.

Application filed February 28, 1917. Serial No. 151,516.

To all whom it may concern:

Be it known that I, FRANK D. POLHEMUS, a citizen of the United States, and resident of Atlantic City, New Jersey, have invented 5 certain new and useful Improvements in Automatic Lubricators for Switch Points, of which the following is a specification.

This invention relates to lubricators for railway switch points and my object is to 10 provide a lubricator for automatically oiling or greasing the plate upon which the switch point slides.

The invention embodies a novel form of combined lubricant reservoir and lubricant 15 discharging means.

An important feature of my invention resides in the manner in which the lubrication is automatically effected, so that after being properly set the device requires no attention 20 whatever on the part of an attendant, except to refill the reservoir when emptied.

Referring to the drawing in which like numerals of reference designate corresponding parts throughout the several views,

25 Figure 1 is a perspective view.

Fig. 2 is a transverse sectional view.

Fig. 3 is a plan view, and

Fig. 4 is a sectional view showing the discharging mechanism enlarged.

30 Fig. 5 shows a modification of the valve structure.

In the accompanying drawing the numeral 1 represents the web of the rail and 2 the base thereof.

35 The lubricant reservoir 3 is substantially rectangular and is secured to the rail by means of bolts 4. The bottom of the reservoir 3 inclines slightly so that it may rest on the inclined surface of the base plate 2.

40 In the top of the reservoir 3 I provide an opening 5 through which oil is poured to fill the reservoir. The opening 5 is normally closed by means of a slide 6. When the oil in reservoir 3 becomes exhausted the slide 45 6 is moved longitudinally of the reservoir exposing the opening 5 through which oil is poured to replenish the said reservoir.

Arranged at intervals along the front of the reservoir I provide lubricant discharge 50 valves 7 through which the lubricant is forced onto plates 8 which are secured to the ties 9. The top surface of the plates 8 are inclined rearwardly to meet the inclination of the base 2 of the rail to furnish

a proper supporting surface for the switch point 10.

The valve 7 is composed of a tubular member 11 secured to the reservoir 3. This member is externally screw-threaded and has a coniform recessed head. The externally 60 screw-threaded portion of the tubular member 11 projects through the reservoir while the coniform recessed head is held within the reservoir. Extending through the tubular member 11 is a plunger 12 having a coniform head which fits the recessed head of the member 11, while the opposite end is screw-threaded. Over the tubular member 11 I provide an internally screw-threaded member 13, which is encircled by a coil spring 70 14. The coil spring 14 is held in place by means of a washer 15 and nut 16 screwed onto the end of the plunger 12 to hold it normally closed. The operation of this device is as follows:

When the switch point is thrown into operative position it strikes against the projecting end of the plunger and forces it inwardly, which allows the lubricant to flow into the coniform recessed head of the tubular member 11, thereby filling the same. As the switch point is moved away from its operative position the coil spring bearing against the nut secured to the end of the plunger forces the plunger to its normally 80 closed position, thereby forcing the lubricant out onto the plates upon which the switch point slides and cutting off further flow from the reservoir.

What I claim and desire to secure by Letters Patent is:

1. In combination with a rail, ties, and a switch point, a lubricant reservoir secured to the web of the rail, having a valve closing the opening therein and a stem projecting therefrom in the path of movement of the switch point and adapted to be actuated by the switch point in its movement laterally, substantially as described.

2. In combination with a rail and ties supporting the same, a lubricant reservoir secured to the rail, spring pressed valves controlling the oil discharge from said reservoir, and having stems extending laterally of the wall of the reservoir and operated by the lateral movement of the switch point, substantially as described.

FRANK D. POLHEMUS.
